UNITED STATES PATENT OFFICE.

VINCENT BENDIX, OF CHICAGO, ILLINOIS.

ENGINE STARTER.

Application filed December 17, 1917, Serial No. 207,458. Renewed January 31, 1923.

To all whom it may concern

Be it known that I, VINCENT BENDIX, a citizen of the United States, residing at Chicago, in the county of Cook and State of Illinois, have invented certain new and useful Improvements in Engine Starters, of which the following is a specification.

My invention relates to that type of engine starter and to the transmission or drive portion thereof as exemplified in patents heretofore issued to me, for instance, Patent No. 1,116,369, dated November 10, 1914, and 1,144,097, dated June 22, 1915, which starter is characterized by a prime mover, such as an electric motor, and a transmission or drive for transmitting the power of the motor by means of a screw shaft and driving member thereon to a member of the engine, such as the fly wheel, to be started.

This transmission or drive comprises a screw shaft operated either directly or indirectly by the motor and a pinion mounted on the shaft for longitudinal movement thereon and rotary movement therewith.

The object of my invention is to produce a simple and efficient form of construction characterized more particularly by a ball and groove arrangement as between the pinion and the shaft as compared with screw-threading the pinion upon a screw-threaded shaft.

In the drawing, Fig. 1 is an elevation, partly in section, of a drive embodying my invention and attached directly to the armature of an electric motor; Fig. 2 a cross section on the line 2—2 of Fig. 3; Fig. 3 a plan view of the pinion and a portion of the shaft, and Fig. 4 a sectional elevation of a modified form of construction.

Referring to the particular embodiment of my invention as shown herein, this drive may be operated either directly or indirectly by the electric motor and while I have herein shown the same as driven directly thereby, it will be understood that it may be driven indirectly in suitable manner.

The rotatable member is in the form of a shaft 1 which, in the present instance, is secured to the extended end of the armature shaft 2 of an electric motor indicated at A.

This shaft is provided with a pair of spiral grooves 1^a terminating in more or less abrupt shoulders 1^b. On the outer end of this shaft a stop nut 3 is secured by screw-threading thereon.

The driving member which is mounted on the screw shaft and capable of longitudinal movement thereon and rotary movement therewith and also adapted to engage a part of the engine to be started is here in the form of a pinion 4 adapted to be advanced into meshing engagement with the engine member such as the teeth 5^a of the engine fly wheel 5. This pinion is provided with an axial extension 6 and such pinion extension has a central longitudinal bore to receive the shaft.

The pinion extension has a pair or pairs of balls 7 mounted therein and adapted to project into the bore and to cooperate with the groove in the shaft. By preference and as herein shown I prefer to provide two sets or pairs of these balls arranged diametrically opposite each other and adapted to be held in place by removable plugs 8 screwing into radial sockets communicating at their inner ends with said bore. The inner ends of these plugs have recesses to receive the sides of the balls presented thereon.

To lock the plugs in their proper adjusted position I provide locking means which here consists of a removable plate or plates 9, the number thereof depending of course upon the particular construction. In the present instance there are two of these plates on opposite sides of the extension 6, and the same are secured thereto by the screws 10. Each plate has angular end recesses adapted to fit the angular outer ends 8^a of the plugs.

Describing the operation of my device as herein shown, when the motor is started and the shaft thereby rotated, the pinion will be advanced longitudinally thereon and into mesh with the fly wheel. When the pinion is in full mesh it will contact the nut 3 and be stopped thereby whereupon it will rotate in unison with the shaft and rotate the fly wheel and thereby start the engine. When the engine is started on its own power

the pinion will be demeshed automatically and returned to normal or home position. This return movement of the pinion is stopped by the contact of one of the balls 6 against the abrupt shoulder 1^b at the end of the groove. This construction will effectually prevent any binding of the pinion on the shaft at the end of this return movement.

10 If desired a spring 11 may be interposed between the shoulder 1^c towards the inner end of the screw shaft and the pinion in order to cushion the return movement of the pinion after being demeshed from the fly-wheel.

15 In Fig. 4 I have shown a modified form of construction in which the corresponding parts are given the same reference characters. According to this construction the grooves 20 on the screw shaft run in the opposite direction as compared with those shown in Fig. 1 and as a result the normal or home position of the pinion is at the outer end of the shaft, as shown in Fig. 4. In operation the 25 pinion is advanced longitudinally and inwardly towards the motor in the meshing operation. A spring 12 is interposed between the shoulder 1^c of the shaft and the pinion and is compressed by the latter during the time of meshing engagement with the fly-wheel, with the result that such movement of the pinion is cushioned and a yielding driving connection afforded at the time 30 of the initial rotary movement of the pinion, inasmuch as the rotary driving movement may take place after considerable compression of this spring and before the pinion has been stopped in its longitudinal movement to the left (Fig. 4) by contact of the balls 35 with the abrupt shoulders at the inner ends of the grooves.

I claim:

1. A transmission mechanism for engine starters comprising a rotatable shaft having a spiral groove thereon, and a driving member mounted on the shaft for longitudinal movement thereon and rotary movement therewith, and comprising a body portion having means for engagement with a part of the engine to be started, and also an end extension provided with a bore to receive the shaft and carrying a series of balls projecting into such bore and cooperating with said groove.
2. A transmission mechanism for engine starters comprising a rotatable shaft having a spiral groove thereon, and a driving member mounted on the shaft for longitudinal movement thereon and rotary movement therewith, and comprising a body portion having means for engagement with a part of the engine to be started, and also an end extension provided with a bore to receive the shaft and with radial sockets communicating with the bore, removable plugs for the sockets and balls in the sockets projecting into said bore and cooperating with said groove, said sockets and plugs being arranged in two pairs diametrically opposite each other.

the sockets and balls in the sockets projecting into said bore and cooperating with said groove.

3. A transmission mechanism for engine starters comprising a rotatable shaft having a spiral groove thereon, and a driving member mounted on the shaft for longitudinal movement thereon and rotary movement therewith, said member comprising a pinion body with teeth to mesh with a part of the engine to be started, and also an end extension provided with a bore to receive the shaft and with radial sockets communicating with the bore, removable plugs for the sockets and balls in the sockets projecting into said bore and cooperating with said groove, the inner ends of the plugs having recesses to receive the balls.

4. A transmission mechanism for engine starters comprising a rotatable shaft having a spiral groove thereon, and a driving member mounted on the shaft for longitudinal movement thereon and rotary movement therewith, said member comprising a pinion body with teeth to mesh with a part of the engine to be started, and also an end extension provided with a bore to receive the shaft and with radial sockets communicating with the bore, removable plugs for the sockets and balls in the sockets projecting into said bore and cooperating with said groove, and means for locking said plugs in place.

5. A transmission mechanism for engine starters comprising a rotatable shaft having a spiral groove thereon, and a driving member mounted on the shaft for longitudinal movement thereon and rotary movement therewith, said member comprising a pinion body with teeth to mesh with a part of the engine to be started, and also an end extension provided with a bore to receive the shaft and with radial sockets communicating with the bore, removable plugs for the sockets and balls in the sockets projecting into said bore and cooperating with said groove, said sockets and plugs being arranged in two pairs diametrically opposite each other.

6. A transmission mechanism for engine starters comprising a rotatable shaft having a spiral groove thereon, and a driving member mounted on the shaft for longitudinal movement thereon and rotary movement therewith, and adapted to engage a part of the engine to be started, said member having an extension provided with a bore to receive the shaft and with radial sockets communicating with the bore, removable plugs for the sockets and balls in the sockets projecting into said bore and cooperating with said groove, said sockets and plugs being arranged in two pairs diametrically opposite each other, and two locking plates secured to said member and each cooperating with the two adjacent members of each pair of plugs.

7. A transmission mechanism for engine starters comprising a rotatable shaft having a spiral groove thereon, and a driving member mounted on the shaft for longitudinal movement thereon and rotary movement therewith and adapted to engage a part of the engine to be started, said member having a bore to receive the shaft and carrying a series of balls projecting into such bore and cooperating with said groove, the end of the groove being made abrupt and adapted to be contacted by one of the balls to stop longitudinal movement of the said member on the shaft.

VINCENT BENDIX.
